Primary Examiner—Joel Sincavage**Assistant Examiner—Lavone D. Tabor****Attorney, Agent, or Firm—Harold J. Smith****[57]****CLAIM**

The ornamental design for a toothpaste dispensing toothbrush, as shown and described.

DESCRIPTION

FIG. 1 is an exploded top plan view of a toothpaste dispensing toothbrush showing my new design with the broken lines showing a toothpaste tube and cap being for illustrative purposes only and forming no part of the claimed design; FIG. 2 is an assembled side elevational view of the toothpaste dispensing toothbrush, the opposite side being a mirror image;

FIG. 3 is a bottom plan view of FIG. 2;

FIG. 4 is a right end elevational view of FIG. 2; and,

FIG. 5 is a left end elevational view of FIG. 2.
